UNITED STATES PATENT OFFICE.

JACOB YOUNG, OF NIAGARA FALLS, NEW YORK.

DESIGN FOR A SPOON-HOLDER.

SPECIFICATION forming part of Design No. 25,319, dated March 31, 1896.

Application filed February 15, 1896. Serial No. 579,457. Term of patent 14 years.

To all whom it may concern:

Be it known that I, JACOB YOUNG, a citizen of the United States, residing at Niagara Falls, in the county of Niagara and State of New York, have invented and produced a new and original Design for Spoon-Holders; and I do hereby declare the following to be a full, clear, and exact description of the same, reference being had to the accompanying drawing, forming a part thereof.

The drawing is a perspective view of my newly-designed spoon-holder.

The leading feature of my design consists in a spoon-holder having upper and lower sections supported by a standard and base-piece, the lower section presenting a flat plate having recesses at its edges and provided with a band forming an upwardly-projecting flange at the outer ends of the recesses, while the upper section presents a plate having notches in its edges, the number of notches corresponding with the number of recesses in the lower section, the parts being of ornamental appearance.

25 A designates the base-piece having a circular bottom, from which it curves upward and is ornamented, as shown. To this base-piece is attached a standard D, having an ornamental handle d at its upper end and carrying the upper and lower sections B and

C, respectively. The lower section C consists of a plate C', having a suitable number of tapered recesses c, which are closed at their ends by a band C'', said band projecting above the plate and being of ornamental appearance. The upper section B comprises a disk, the intermediate portion of which is preferably cut away, as shown, and its outer edge provided with triangular-shaped notches b, the number of notches corresponding with the number of recesses c in the lower section and are properly arranged with respect thereto. The standard is chamfered between the sections B and C, as shown.

The spoon-holder of the design herein shown is made of metal and is ornamental as well as serving to hold spoons or other articles of tableware, which when placed in position thereon add to the general effectiveness of the design.

What I claim is—

The design for a spoon-holder herein shown and described.

In testimony whereof I affix my signature in presence of two witnesses.

JACOB YOUNG.
